UNITED STATES PATENT OFFICE.

JOHN M. SUNDEAN, OF HUDSON, WISCONSIN.

PURSE.

No. 926,908.

Specification of Letters Patent.

Patented July 6, 1909.

Application filed September 3, 1908. Serial No. 451,518.

To all whom it may concern:

Be it known that I, JOHN M. SUNDEAN, a citizen of the United States, residing at Hudson, in the county of St. Croix and State of Wisconsin, have invented a new and useful Purse, of which the following is a specification.

This invention relates to coin purses.

The object of the invention is to provide a purse of this character having a novel form of closure for the mouth of the purse, the closure being of such character as to permit of its ready manipulation for the purpose of permitting access to the interior of the purse for the purpose of selecting and removing coins therefrom, and which shall be so constructed and arranged as to be positive in preventing the accidental escape of money when once closed.

20 A further object is to adapt a purse for carrying coins and paper money, and to cause the security of both against loss to be equal.

With the above and other objects in view, as will appear as the nature of the invention 25 is better understood, the same consists in the novel construction and combination of parts of a coin purse as will be hereinafter fully described and claimed.

In the accompanying drawings, forming a 30 part of this specification, and in which like characters of reference indicate corresponding parts:—Figure 1 is a top plan view of a purse constructed in accordance with the present invention, showing the closure closed. Fig. 2 is a similar view showing the closure 35 opened. Fig. 3 is a vertical transverse sectional view through the purse shown in Figs. 1 and 2. Fig. 4 is a vertical longitudinal sectional view through a slightly modified form 40 of purse. Fig. 5 is a perspective detail view of a closure for the coin purse shown in all of the figures.

The purse shown in Figs. 1, 2, and 3 comprises a circular back 1, an annular front 2, 45 a closure designated generally 3 and an annular closure guide or keeper 4.

The back, front and keeper will be generally constructed of leather, while the closure will be constructed of some substance having 50 relative rigidity and flexibility such as indurated fiber, metal, or artificially stiffened leather. As shown in Fig. 5, the closure comprises a disk 5 which is provided with an approximately semi-circular opening 6, constituting a mouth of a size to permit inspection and removal of the coins contained by

the purse. The mouth is adapted to be opened or closed by a semi-circular cover 7, which is somewhat greater in diameter than the mouth, and is held assembled with the 60 disk or body 5 by an eyelet 8. The disk is secured to the front by a circular row of stitches 9, and to the keeper by a similar circular row of stitches 10, while the front and back are secured together by a circular row 65 of stitches 11. The cover has secured to it by an eyelet 12 a tab 13 by which the cover may be rotated to open and close the mouth as will be obvious by reference to Fig. 2. The connection between the front and the 70 back and the closure is such as to permit the purse to be distended so as to adapt it to contain a suitable amount of silver or other coin. While it will generally be preferred to make the back and front circular as shown, yet as 75 will be obvious these parts may be polygonal in contour, and still be within the scope of the invention.

In the form of the invention shown in Fig. 4 the front 14 is extended to form one side of 80 an elongated pouch, the other side of which is formed by elongating the back 15. This arrangement will cause the bag or pouch 16 formed by the elongated back and front to contain a large amount of coin. As a further object in elongating these parts, namely 85 to adapt these purses for carrying paper money, and this is secured by attaching a third flap 17 to the front and back by a row of stitches 18 that extends around the bottom and edges of the three extensions. This third flap provides in combination with the back 15 a pocket 19 in which paper money 90 may safely be deposited, and when the extension of the pouch formed by the parts 14, 15 and 17 is folded upon itself, the paper money placed in the pocket 19 will be securely housed, but at the same time will be 95 ready of access.

The improvements herein defined, while 100 simple in character, will be found thoroughly efficient and will not require the provision of special machinery in their construction.

I claim:—

1. A purse comprising a flexible back, an annular flexible front secured thereto, and a closure comprising a rigid apertured disk secured to the front, and carrying a cover 105 slideable over the aperture.

2. A purse comprising a flexible back, an annular flexible front secured thereto, a clo-

sure secured to the front, said closure comprising a rigid apertured disk, and a cover carried by the disk and slideable over its aperture, and a keeper for the closure comprising

5 an annular member secured to the disk and overlapping the cover.

In testimony that I claim the foregoing as

my own, I have hereto affixed my signature in the presence of two witnesses.

JOHN M. SUNDEAN.
